UNITED STATES PATENT OFFICE

ALBERTO TER VEHN, OF BUENOS AIRES, ARGENTINA

LIMIT SWITCH

Application filed September 28, 1927. Serial No. 222,578.

The present invention relates to pumps for dispensing oil, gasoline and similar liquids, and particularly to pumps of the above character which are electrically actuated and in which the measurement of the liquid to be dispensed is effected automatically. More specifically, the invention resides in the provision of an improved limit switch for automatically controlling the current supply, such switch acting to interrupt automatically, under predetermined conditions, the circuit wherein the motor that drives the pump is included.

In the accompanying drawing:

Figure 1 is a front view of the improved limit switch;

Fig. 2 is a part-sectional side view thereof;

Figs. 3 and 4 are fragmental perspective views, in different positions, of the springs which constitute the electric contacts.

In the construction illustrated, 9 indicates the operating shaft of the apparatus which is connected to be driven from an electric motor (not shown) of any approved design and itself acts to drive the pump proper (also unillustrated).

To effect the starting and stopping of the motor, in order to actuate the pump and also to adjust its work in accordance with predetermined quantities of liquid, the following

parts or devices are provided: To the shaft 9, there is secured a gear 36 which meshes in a predetermined relation with another gear 37 fixed to a shaft 41; the ratio being in this instance 1:4, so that for each four complete strokes of the pump piston (which has a driving connection with shaft 9), the gear 37 will make one complete revolution. Assuming that at each effective stroke of the piston the volume of liquid drawn in is equivalent

to 5 liters, for instance, one complete revolution of gear 37 will correspond with the discharge of 20 liters. Gear 37 has secured to it a disc 38 of insulating material, and at the central part of said disc there is secured a metallic conducting disc 40. The insulating disc 38 carries a set of stops 39, spaced at convenient intervals apart, say 90°, and arranged radially.

42 is a member of insulating material and providing a support for the contact member

43 which carries a spring contact 44, said spring contacting continuously with the metallic disc 40, as may be clearly seen from Figs. 1 and 2. On the said insulated support 42, there is mounted a contact carrier 45 to which is fixed a spring contact blade 46 which may be pressed against the surface of disc 40 by a button 47, said blade being held in its tensioned or compressed position by means of a spring catch or detent 49 carried by a bracket 48 on the support 42. The detent 49 is provided with a cut-away part 50 permitting it to pass over the disc 38 and to be engaged contiguous to the said cut-away part by the stops 39 of disc 38. 50' and 51 are the terminals corresponding to contacts 46 and 44, respectively, and to which terminals are connected, the wires 52-53 leading from a suitable source of current (not shown).

The apparatus further includes a main switch of approved character for throwing the entire apparatus into ineffective condition, for instance at night; and with the arrangement shown and described, it is evident that by acting on spring 46 by means of push-button 47, said spring, owing to its resilience, will contact with conducting disc 40, thereby closing the motor circuit and starting the operation of the pump.

Rotation of shaft 9, as will be apparent, effects rotation of gear 37 and the members secured to it and, consequently, at a certain movement, one of the stops 39 will strike against the part 50 of the detent 49 (see Fig. 3) and flex the latter rightward so that it will be released from engagement with the free end of spring 46 which, due to its resilience, will then assume the position shown in Fig. 4, separated from conducting disc 40, thereby opening the circuit and causing the motor to stop. The stop 39, as the counter-clockwise rotation of disc 38 continues, will ultimately pass by the part 50 of the detent to the other side thereof, this taking place about the same (or substantially the same) time that said detent is disengaged from a spring 46. The apparatus is ready for a further operation when the Fig. 4 position of the parts is assumed; the angular distance between the stops 39 governing the number of

revolutions of shaft 9 and, accordingly, the quantity of liquid discharged, since the latter is invariably the same for each stroke of the pump.

5 I claim:

1. A limit switch for an electric circuit, embodying a driven insulating disc, a conducting disc fixed thereto, a set of coacting flexible contacts, one of which is adapted to engage the conducting disc and thereby complete the circuit, means for holding said contact in such engagement, and releasing means carried by the insulating disc for terminating said engagement automatically.
- 10 2. A switch according to claim 1, in which the set of contacts includes a spring blade constantly engaging the conducting disc, and a second blade normally spaced from said conducting disc but adapted to be moved into contact therewith, and in which the contact-holding means acts to hold the second blade in contacting position but is released by the releasing means on the insulating disc.
- 15 3. A limit switch for an electric circuit, embodying a driven insulating disc, a conducting disc fixed thereto, a spring blade constantly engaging the conducting disc, a second blade normally spaced from said conducting disc but adapted to be moved into contact therewith, a spring detent acting to engage the second blade and hold it in contacting position, and a projection on the insulating disc adapted to strike said detent and disengage it from the second blade.
